UNITED STATES PATENT OFFICE.

ALEXANDER W. STEWART, OF CHICAGO, ILLINOIS.

WIRE MATTRESS.

SPECIFICATION forming part of Letters Patent No. 251,482, dated December 27, 1881.

Application filed November 8, 1881. (No model.)

To all whom it may concern:

Be it known that I, ALEXANDER W. STEWART, residing at Chicago, in the county of Cook and State of Illinois, and a citizen of the United States, have invented new and useful Improvements in Wire Mattresses or Bed-Bottoms, of which the following is a full description, reference being had to the accompanying drawings, in which—

10 Figure 1 is a top or plan view; Fig. 2, a side elevation; Fig. 3, an enlarged detail, being a top or plan view, showing one of the connections between the end bar and mattress, the end bar and mattress being broken away; Fig. 15 4, a longitudinal section of the parts shown in Fig. 3; Figs. 5 and 6, enlarged details, showing a modification in the form of the connecting devices for the end piece and mattress.

The object of this invention is to attach what 20 are known or termed "wire" mattresses or bed-bottoms to the supporting-frame or end pieces in such manner as to enable the proper strain to be placed upon the fabric, and have the attaching devices simple in construction and easily applied, and form a support for the mattress or bed-bottom, whether the same lies horizontal or is in a folded condition, the attachment also being firm and unyielding and not liable to tear out or give way in use; and its 25 nature consists in providing a wire mattress or bottom having its ends flattened and covered and protected by a binding of sheet metal or other material; in providing a tie or strengthening-rod running through the mattress transversely between the binding-strip and held in place by riveting or otherwise securing the binding to the mattress; in providing a secondary tie or strengthening-rod located transversely of the binding-strip, and the outer edge thereof 30 to receive and furnish a support for the attaching eyes or hooks; in providing retaining and sustaining hooks and a coupling and tie rod and eyebolts for attaching the end of the mattress to the frame or support; and in the 35 several parts hereinafter set forth, and specifically pointed out in the claims as new.

In the drawings, A represents the wire mattress or bed-bottom; B, the binding-strips; C, the connecting links or hooks; D, the sustaining strap or bar; E, the tightening or draw bolt or hook; F, the receiving-nut; G, the eye-

bolts entering the end rails or support; H, the coupling or tie rod; I, the end rails or supports; J, a form of nut which can be used in connection with the eyebolt G to tighten or draw the mattress to place; a, the flattened end of the mattress; a', the rivets passing through the flattened portion of the mattress and the binding-strip; b, the tie or strengthening rod; b', the rivets passing through the mattress and 55 binding-strip forward of the tie-rod; c, the tie or strengthening rod for attaching the hooks or links; c', the openings in the binding-strip for passing the links or hooks around the rod c; d, the eye or ring receiving the link or hook C; 60 d', the head or enlargement for the nut F; f f', cross-bars forming stops for the nut F; e, the opening or eye at the end of the draw bolt or rod E; g, the eye or opening of the eyebolt G; h, the flange or rim of the nut J; i, the body 65 or receiving portion of the nut J; j, the opening or cavity through the rim and into the body or receiving portion i.

The wire mattress A may be made in any 70 of the usual and well-known forms, except that its ends are both compressed so as to form a flat portion or surface, a, over which the binding-strips are placed, a binding-strip being used at each end, as shown in Fig. 1. These binding-strips may be made of sheet 75 metal or other suitable material which can be bent or otherwise formed into shape to furnish a perfect binding for the ends. This binding may be formed of a single piece of material turned or bent over, as shown, to form 80 adjacent sides or surfaces, between which the end of the mattress is passed, or it may be formed of two independent pieces bent or turned to lap each other at the edge of the mattress. This binding is attached to the flattened portion a by passing rivets a' through 85 it and the binding, so as to firmly rivet the binding to the mattress end.

The rod b is passed transversely through the mattress between the binding, and is held 90 in place by rivets b' passing through the binding and the mattress just forward of the rod b, and this rod is for the purpose of furnishing additional strength and resistance to the strain of the mattress in use, and relieves the 95 rivets a' from sustaining the entire strain.

The rod c is located transversely of the bind-

ing-strip at the outer edge, and, as shown, is held in place by bringing the strip from which the binding is formed over and around and in close contact with the rod; but it may be 5 locked or secured in some other suitable manner. This rod receives one end of the link or hook C, the end of each hook being passed around the rod through an opening, c', formed in the binding-strip forward of the rod c. These 10 hooks C may be formed, as shown, so as to have an eye or opening at each end, and may be made of round iron or other suitable material, which can be formed into the shapes shown or other shapes, having eyes or openings at both ends.

The frame or link D may be made of malleable iron or other material which can be cast or formed into shape to have a main or body portion with a longitudinal recess and end 20 portions, d d', one of which, d, has an eye or opening by which the link or frame can be hooked on or attached to the hook or link C, and the other end is enlarged somewhat, and has an opening therein to receive the nut for 25 the draw-bolt E.

Each nut F may have an exterior of the form shown, or other form adapted to receive a wrench for turning the nut and drawing the fabric to place. As shown, the link or frame 30 D has cross-bars f f', located on opposite sides of the nut and of the frame, which cross-bars form stops against which the nut F works.

The draw-bolt E has its shank or body screw-threaded to receive the nut F, and at one end 35 is provided with an eye or opening, e, by means of which it is attached to an eye, G, the shank of which enters the end rail or support, I, the eye G having a suitable opening, g, to receive the eye d. The links or hooks C, frames or 40 links F, draw-bolts E, and eyes G form the devices for attaching one end of the mattress to its frame or support, and the other end of the mattress is attached to its end or support by hooks C, similar to the corresponding hooks at 45 the other end, and hooked to the rod c by passing one end around the rod and through the opening c', and attached at the other end to a coupling or tie rod, H, which rod passes through the eye or opening at this end of each link C 50 and through the ends or openings of the eyes G, the shanks of which enter the end rail. By this arrangement the mattress or bottom is attached to its end rail or supports at one end by the eyes G, coupling or tie rod H, and links or 55 hooks C; and at the other end by the eyes G, draw-bolts E, frames or links F, and links or hooks C; and as many of these devices as are required to furnish the necessary support and strength are to be used, the number depending 60 upon the width of the mattress or bed-bottom. The mattress or bottom is drawn taut or strained by turning the nut F with a wrench or other suitable device, shortening the bolt E and drawing the link or frame F toward the end rail or 65 support, I, suspending the mattress or bottom from or between the end rails or supports, so

as to give any required degree of elasticity or strain; and by using the binding-strips B in connection with the strengthening or tie rods b c it will be seen that a great strain can be 70 placed on the fabric without danger of separating the strands at the end. This method of supporting and straining a mattress or bed-bottom can be used for the various purposes and in the various places for which such mattresses or bed-bottoms are employed, and will be found especially adapted for use in what are known or termed "folding beds," as it enables the fabric or mattress to be folded with the bed-clothing inclosed, the hooks or links turning 80 or dropping down out of the way, so as to give or furnish sufficient room for the clothing.

For some purposes the secondary tie or strengthening rod need not be used, as the binding itself will be sufficiently strong to suspend and support the fabric; but where a great amount of strain is desired it will be found best to use these tie or strengthening rods c.

In some cases the link or strap D, with the tightening-bolt E, can be dispensed with, and 90 the necessary amount of strain can be provided for by the eyes G, and when so used the shank of the eyes enters a screw-threaded opening formed in a nut, J, having a body or receiving portion, i, and a flange or rim portion, 95 h, with a central cavity, j, as shown in Figs. 5 and 6. The rim or flange h may be formed as shown or otherwise, so as to receive a wrench by which it can be turned, and the body or receiving portion of this nut is to be driven into 100 the end rail so as to fit somewhat tightly, and prevent its becoming misplaced or dropping out easily, and at the same time not interfere with the nut being turned to draw the fabric taut. When this form of construction is used 105 the hook or link C hooks directly into the eye or opening of G, as shown in Fig. 6.

Hooks secured rigidly to the binding-strip to receive the end d of the link or frame D might be used, in which case the hooks or links 110 C could be dispensed with, the links or frame D permitting of sufficient movement to allow the mattress or bed-bottom to be folded.

In some cases where a great strain is desired the nuts J could be used in addition to the 115 draw-bolt E; but for general use the draw-bolt E will be found sufficient.

By using the method of drawing herein shown and described it will be seen that the end piece or support can be rigidly secured in 120 position and the mattress be drawn toward the end piece or support, straining the mattress to any desired degree, and this straining will be accomplished more readily and easily than in the usual manner by moving the end 125 piece or support.

If desired, the link or frame and draw-bolt, with connection, could be used at both ends of the mattress. The coupling-rod could be dispensed with and the mattress be attached by 130 the links C and eyebolts G by interlocking them.

What I claim as new, and desire to secure by Letters Patent, is—

1. A wire mattress or bottom, A, having its ends flattened and bound by one or more strips, B, at each end, to resist the strain in use, substantially as specified.
2. A wire mattress or bottom, A, having its ends flattened and bound by one or more strips, B, and provided with tie or strengthening rods, b, to resist end strain and to prevent drawing out at the end, substantially as described.
3. A wire mattress or bed-bottom, A, having its ends covered by a binding, B, in combination with the attaching and sustaining hooks or links C, for suspending the mattress, substantially as set forth.
4. A wire mattress or bed-bottom, A, having its ends flattened and covered by a binding, B, and provided with the tie or strengthening rods b, in combination with the attaching and sustaining hooks or links C, for suspending the mattress and supporting the same under strain, substantially as specified.
5. The tie or strengthening rods c, in combination with the flattened and bound ends a of a wire mattress or bed-bottom and the attaching and retaining hooks C, for suspending the mattress, substantially as and for the purpose specified.
6. The links or frames D, draw-bolts E, and nuts F, in combination with the links or hooks C and the rod c, and a wire mattress or bed-bottom, A, for straining the mattress, substantially as specified.

7. The frame or link D, draw-bolt E, nut F, and eye G, in combination with the links or hooks C and wire mattress A, for attaching the mattress and drawing it taut, substantially as specified.

8. The frame or link D, draw-bolt E, and nut F, in combination with the link or hook C, binding B, and mattress A, substantially as and for the purposes specified.

9. The frame or link D, draw-bolt E, nut F, and eye G, in combination with the link C, rod c, binding B, and wire mattress A, substantially as and for the purposes specified.

10. The wire mattress A and binding B, in combination with the links or hooks C, tie or coupling rods H, and eyes G, for attaching the mattress to the end rail or support, substantially as specified.

11. The wire mattress A, having its end flattened and bound by a binding, B, provided with a tie or strengthening rod, c, in combination with the hooks or links C, coupling or tie rod H, and eyes G, substantially as and for the purpose specified.

12. The nuts J and links or hooks C, in combination with the wire mattress A and binding B, substantially as and for the purpose specified.
